UNITED STATES PATENT OFFICE

LARS H. VOLD AND KARL R. HAMMERSTROM, OF BUTLER, PENNSYLVANIA

TRIPLE-PUNCH MECHANISM

Application filed February 3, 1927. Serial No. 165,600.

This invention relates to multiple punch mechanism, more particularly to punch presses in which a plurality of punches are disposed in angular spaced relation and actuated by a common drive shaft.

It is among the objects of this invention to provide a multiple punch press that is especially adapted for the punching of structural members such as angles, channels, I-beams, 10 Z-bars and the like, and which shall be adapted to simultaneously punch the several sides or legs of such members by a single pass of the work through the machine tool.

Another object of the invention is to provide a punch mechanism which shall be especially adapted for the punching of American Railway Association channel sections and Z-bars employed in railway vehicle structures, and which shall be further adapted for 20 simultaneously punching a plurality of Z-bars, angles and the like.

Another object of the invention is to provide a punch mechanism embodying a centering device which shall function to always 25 return the work such as the channel section to a central position relative to the die block so as to correctly gage the channel for web punching.

Another object of the invention is to provide cam operated strippers which are designed to clamp the work firmly against the die block to properly engage it, to strip the work off the punch when the latter recedes and subsequently release the material for 35 spacing.

Still another important object of the invention is to provide a multiple punch mechanism of simple, and durable, mechanical construction, which shall be efficient in its 40 operation of simultaneously acting on the several faces of a structural steel member to perforate its walls.

In the accompanying drawings constituting a part hereof and in which like reference 45 characters designate like parts, Fig. 1 is a side elevational view partially in section of a multiple punch press embodying the principles of this invention; Fig. 2 is a side elevational view thereof; Fig. 3 an enlarged detail illustrating the cam operated stripper

mechanism; Fig. 4 a detail view partially in elevation and partially in section illustrating the invention as applied to the punching of Z-bars; Fig. 5 a similar detail view illustrating the punching of an A. R. A. channel member; Fig. 6 a plan view diagrammatically illustrating the relative positions of the die blocks, punches and stripper mechanism; and Fig. 7 is an end elevational view of a centering device employed for the punching of channel members.

With reference to Figs. 1 and 2 of the drawings the structure therein illustrated comprises a machine housing or frame 1 having a central opening 2 and a removable bolster 3. The frame is provided with guides 4, 5 and 6, respectively, for removably mounting a plurality of punch holders 7, 8 and 9, each of which is adapted to carry one or more punches. The movable punch holders 7, 8 and 9 are connected by suitable mechanical linkage to be simultaneously actuated by an eccentric drive shaft 10 journaled at the upper right hand portion of the machine frame and secured by a bearing block 11. The linkage connecting the movable punch elements with the eccentric drive shaft 10 comprises a rocker 12 and a plurality of levers 13 and 14, pivoted at 16, 15 and 17, respectively to the machine frame. The rocker 12 and the lever 13 are connected by a link 18 at 20 and 19, respectively and the rocker 12 and lever 14 are joined by a link 21 connected at 22 and 23. The rocker and levers 12, 13 and 14 are pivotally connected at 25, 24 and 26 respectively, to links 28, 27 and 29 that have pivotal connections at 31, 30 and 32, respectively, with the movable punch supporting members 8, 7 and 9. The rocker 12 is pivotally connected at 33 with a connecting rod 34 which is the connecting element of the movable punch holder actuating mechanism and the eccentric drive shaft 10.

The removable bolster 3, Figs. 1 and 2, is provided with a central cut-out portion 36 and T-slots 37 for mounting and securing a die block 38 which carries the die 39, Fig. 2.

The die 39 illustrated in Fig. 2 is adapted for the punching of channels or A. R. A.

beams as illustrated and in punching the latter a plurality of punches 40 are provided which are adapted to act upon the double flanged face 41, the web 42 and the flange 43 by a single pass of the structural member or work through the machine. The punches 40 may be controlled to act either simultaneously or consecutively upon the work by the operation of gag blocks and spacing mechanism,

10 the gag blocks being effective in rendering certain of the punches rigid for punching for a given stroke of the punch holders and the spacing mechanism being adapted to advance the work between punching intervals. Both 15 the gag block operation and the automatic spacing are coordinated and made fully automatic by a paper tower mechanism as set forth and described in our copending application Serial No. 146,192, filed Nov. 4, 1926.

20 The machine operating mechanism and the control mechanism have been diagrammatically shown in Fig. 2, and this mechanism comprises a paper-tower generally designated at 45, which automatically controls the 25 gag block for the punches 40. The paper-tower 45 also controls the spacing mechanism of which the swing frame 46, the pitman 47 and the connecting gear trains 48 are shown.

The swing frame actuates the ratcheting 30 pawl for the work spacing mechanism and is positively connected through the gear train 48 to the eccentric drive shaft 10.

As shown in Fig. 2 and as is more clearly 35 illustrated in the enlarged detail of Fig. 5, an extension 50 is provided to cooperate with the die 39 for punching A. R. A. sections of the form illustrated. The member 50 is adapted to engage the web portion 42 of the section and functions as a stripper when the 40 punches 40 are withdrawn from the work.

In the punching of channels and A. R. A. sections it is necessary to maintain the work in a central position relative to the web punching dies to correctly gage for web 45 punching. This is accomplished in accordance with the present invention by a centering device illustrated in Fig. 7, which comprises a base 51 secured to the bolster 3 by bolts 52 that are disposed in the T-slots 37 50 of the bolster. On the base are arranged a pair of opposing slides 53 and 54 which carry rollers 55 and 56, respectively. The rollers are adapted to engage the flanges of the channel members mounted on the die 39, 55 and the slides 53 and 54 are adjusted by set screws 57 so that the rollers 55 and 56 just clear the channel member in its central position. The set screws 57 bear on a fixed block 58 and the slides 53 and 54 are biased 60 by a coil spring 59 in the direction of the block 58 to maintain contact of the rollers 55 and 56 with the channel member. The coil spring 59 is disposed between a collar 60 and washer 61 carried by a spindle 62 65 that extends through openings provided in

the slides 53 and 54. The tension of the spring 59 may be varied by adjusting the nuts 63 and 64 on the spindle 62. There are two centering devices such as shown in Fig. 7 mounted on the bolster 3, one at the front 70 and one at the rear for the purpose of maintaining the channel under the influence of one or the other of them during the punching operation.

For punching angles and Z-bars special 75 stripper devices are employed as shown in Figs. 3, 4, 6 and 7. Referring to Fig. 3, which illustrates the punching of Z-bars, a compound stripper 65 is shown in cooperative alignment with the Z-bars, the stripper being adapted to engage the top flanges of the Z-bars by its vertically depending portions 66 and its movable side portion 67, the latter engaging the web portion between the divergent flanges of the Z-bar members and its lower flange. The legs 66 of the stripper are vertically movable, to contact with the Z-bars, by virtue of a cam actuated mechanical linkage that is connected to the movable portion 67 of the stripper by pivotally connected links 68. The side stripper members 67 are pivotally connected to the top stripper member at 69.

The connecting links 68 of the stripper are pivotally connected at 70 to levers 71 that are pivoted at 72 to the machine frame. The levers 71 are connected by a pin 73 that is movably disposed in a slotted opening 74 of vertically reciprocating gear-tooth racks 75. The rack members are provided with 100 gear teeth 76 and are mounted in guideways to be vertically movable therein. Reciprocatory movement of the rack 75 is effected by gear segments 77, the teeth 78 of which engage the teeth 76 of the rack member. The 105 gear segment members are mounted on rock shafts 79 which are inter-connected by levers 80 and connecting links 81 and 82 and lever 83. One of the rock shafts 79 is connected by a lever 84 to a push rod 85 which extends through a suitable opening in a cam follower 86. A coil spring 87 is provided at the extended end of the rod 85 and secured in position by a suitable nut and washer 88 and 89, respectively. The follower 86 is provided with a roller 90 that is in surface contact with a cam 91. The cam is mounted on the eccentric drive shaft 10 to provide for the proper timed relation between the relative movements of the strippers and the several punch holders.

As shown in Fig. 6 the side stripper members 67 are pivoted at 69 and are provided with shoes 67a pivoted at 92 to permit the faces 93 thereof to align with the work when brought into engagement therewith. The side strippers 67 by virtue of the shoes 67a and their pivotal mounting are constituted teeter members to assure engagement of the strippers over a relatively large area of the 125 130

Z-bar or other structural member which it is adapted to hold against the die block.

Referring to Fig. 4 of the drawings the relative positions of the several punches and the stripper members, illustrate how they cooperate in acting upon a plurality of Z-bars for the punching operation. The punches 40a for example act upon the web of the Z-bars to perforate them, the punches 40b on the lower leg or flange and the punches 40c on the upper leg or flange. An adjustable set screw 95 is provided in the upper stripper, the adjustment of which regulates the spacing of the engaging faces of the upper stripper member and the work.

With particular reference to Figs. 1, 3 and 4 of the drawings, the operation of this device is briefly as follows:

As shown in Fig. 4 the strippers are clamping the Z-bars hard on the die blocks for gaging. When the respective punches act to withdraw after penetrating the Z-bars the strippers are actuated to release the Z-bars by cam action, as illustrated in Fig. 3. At 170 degrees the cam starts to lift the strippers away from the Z-bars, the stripper, cam and spacing mechanism is so timed and regulated that the spacing of the work to advance it along the die starts at 180 degrees of the cam at which point the strippers are disengaged from the work, leaving the material free to move. At 355 degrees the cam starts the strippers down to engage the work. The strippers come in contact with the material to be punched at approximately 12 degrees; at 20 degrees of the cam the punches will strike. The stripper, spacing and punching mechanism is designed to be adjustable to provide for the proper coordination of the strippers, punches and spacing mechanism for different thicknesses of material within the limits of the machine.

The centering device as illustrated in Fig. 7 is employed in the punching of channels and A. R. A. sections and functions in the following manner: When punching the flange shown in Fig. 7 the channel is shoved up to the die by the punch and the centering device returns the channel to a central position so as to gage correctly for web punching. The centering device functions in a similar manner in the punching of A. R. A. sections illustrated in Fig. 5 which are commonly employed in sub-frame structures of railway vehicles.

The multiple punch press is designed to adapt it for use in the punching of a variety of structural steel shapes, but it is particularly designed for the punching of a plurality of Z-bars simultaneously, and A. R. A. sections which are commonly employed in railway car construction. The utilization of automatic strippers and the cam-actuated operating mechanism therefor permits the coordinating of the strippers with the move-

ment of the punches. The centering device and the strippers function to correctly gage the work for punching and to hold it against the die. It is possible with this type of multiple punch press to complete the punching of structural shapes of any length by perforating the webbed angles or legs in a single pass of the work through the machine. The use of the automatic stripper and the centering device also provides for the allowance of necessary clearance to permit the material or work to slip off the dies slightly to withdraw the fins, formed by punching, from the die before the spacing starts. The fins are caused by imperfect dies and punches and are very troublesome and must be shorn off in spacing unless they are withdrawn from the dies in this manner.

It is evident from the foregoing description of this invention that multiple punch presses made in accordance therewith provide efficient and automatic means for simultaneously acting upon the several faces of the work to be punched by a single pass of the work through the machine. It is further evident that the coordination of the strippers, centering device and punches in the manner herein set forth permit the utilization of an automatic spacing or feeding mechanism for the work, and a paper-tower control for the punches and the spacing mechanism, as is the subject matter of a copending application herein referred to, thus rendering the entire operation of the machine automatic and therefore positive.

Although the machine herein illustrated features the punching of Z-bars, A. R. A. channel sections, and straight channels it will be obvious to those skilled in the art that the machines may be readily adapted for the punching of any of the well known structural steel shapes.

We claim:

1. In a punch-press the combination with a plurality of punch-holders mounted for reciprocatory movement in rectangular spaced relation, punches carried thereby, an eccentric drive shaft therefor, a rocker connected to said shaft, a plurality of rocker levers pivotally connected to said holders and positive links connecting said rocker levers to said rocker whereby rendering said holders simultaneously operative by said drive shaft.

2. In a punch-press the combination with a plurality of punch-holders mounted for reciprocatory movement in angular spaced relation, punches carried thereby, an eccentric drive shaft therefor, a rocker operatively connected to said shaft, and a plurality of levers and links connecting said holders and said rocker to render said holders simultaneously operative by said drive shaft.

3. In a punch-press the combination of supporting die blocks for punching structural sections, a plurality of punch-holders adapted

for reciprocatory movement and disposed in respectively rectangular spaced relation to each other and to said die blocks, one or more punches mounted in said holders for perforating said sections, an eccentric drive shaft 5 for reciprocating said holders, a rocker connected to said shaft, a plurality of rocker levers connected to said holders, and positive links connecting said levers to said rocker whereby to simultaneously actuate the holders for punching all sides of the work in a single pass.

4. In a punch-press the combination of one or more supporting die blocks adapted to engage the web and flanges of structural sections to be acted upon, an eccentric drive shaft therefor, a plurality of punch-holders adapted for reciprocatory movement and disposed in rectangular spaced relation to said die block or die blocks, one or more punches 15 for perforating said sections mounted in said holders, a rocker mounted on said drive shaft and positive lever connections from said rocker to the punch holders for simultaneously actuating said holders for punching the web and flanges of the sections in a single pass.

5. In a punch-press the combination of a work supporting die block, a plurality of punch-holders adapted for reciprocatory movement and disposed in angular spaced relation with said die block, punches mounted 30 in said holders, cam actuated multiple part strippers for gaging the work on said die block and for stripping the work from said punches, said stripper parts being linked together and adapted by conjoint action to both vertically and horizontally engage the work, and a centering device mounted adjacent to 35 said die block for centering the work thereon and adapted to operate independently of said strippers.

6. In a punch-press the combination of a work supporting die block, a plurality of punch-holders adapted for reciprocatory movement and disposed in angular spaced relation with said die block, punches mounted 45 in said holders, and cam actuated pivotally connected multiple part strippers adapted to engage the work at spaced intervals, said strippers being adapted to conjointly engage the work at the top and sides of the die block simultaneously to hold it for punching and subsequently release it for spacing.

55 7. In a punch press the combination of a plurality of punch holders mounted to reciprocate in angular spaced relation with respect to a common die block, punches carried thereby, an eccentric drive shaft, a rocker 60 driven thereby, positive operating connections from said rocker to each of said punch holders, and multiple part pivotally connected clamping and stripping members positively connected to said drive shaft and 65 adapted to operate in synchronized coordi-

nated relation to said punch holders and both vertically and horizontally engage the work.

8. A punch press mechanism for straight structural sections having rectangularly disposed walls comprising a die block, clamping devices for holding the stock on the block and for stripping it from the punches, an eccentric drive shaft, a rocker connected to be driven by the shaft, rocker levers connected to the first rocker by positive links, punch 70 holders mounted to reciprocate horizontally on opposite sides of the die block and connected to said rocker levers so as to be reciprocated thereby, punches carried thereby, and another punch holder carrying a punch 75 mounted above the die block and adapted to be reciprocated vertically by the first rocker.

9. In a punch press for standard structural sections, the combination of a supporting die block, a plurality of punch holders mounted to reciprocate in angular spaced relation about said die block, punches mounted in said holders and a centering device for centering the work upon the die block, said centering device comprising a detachably mounted 80 base member, a pair of opposing slide members 85 movably mounted upon said base member, a pair of rollers mounted upon said slide members and arranged to engage the edges of the work on opposite sides of the die block, means for selectively adjusting said slide members and rollers to provide for the reciprocation of different shapes of stock, and resilient means biasing said slide members toward a selected position.

10. In a punch press for standard structural sections, the combination of a work-supporting die block, a plurality of punch holders mounted to reciprocate in angular spaced relation about said die block, punches mounted in said holders, and a pair of centering devices for centering the work upon the die block, said centering devices being arranged in such a way that the work is at all times under the influence of at least one of them, and each comprising a securely mounted base member, a pair of oppositely disposed rolls yieldably and adjustably mounted upon said base member and adapted to bear upon the opposite edges of a piece 95 of stock mounted upon the die block.

11. In a punch press for structural sections the combination of a die block having a plurality of work-engaging side walls, a plurality of punch holders mounted to reciprocate in angular spaced relation about said die block, punches mounted in said holders, and a combined gauging, clamping and stripping mechanism for gauging the work and clamping it on the die block, stripping it from the punches and then releasing it, said mechanism comprising a work-engaging member for each of the work-engaging side walls of the die block, means pivotally connecting said latter members together, and 120
